ABSTRACT: An auxiliary lift attachment is disclosed for use with a lifting device such as a fork lift truck used to lift and handle a dump box of the type having a lifting lug extending rearwardly from its rear wall. The lift attachment comprises a vertical track member and a lifting member movable along such track for engaging and raising the lift lug of a box carried by the lifting device. Raising movement of the lifting member is obtained from the normal lifting movement of the lifting device carriage and by means of a flexible member having one end attached to the lifting member and passing upwardly over a wheel at the upper end of the track member, the other end of such flexible member being connected to the stationary vertical mast of the lifting device.

AUXILIARY LIFT ATTACHMENT FOR A LIFTING DEVICE

BACKGROUND OF THE INVENTION

This invention relates to lifting devices, such as fork lift trucks, used to pick up, lift and transport from place to place various articles, and deals more particularly with an attachment for such a lifting device to adapt it to use in picking up and dumping dump boxes.

The lifting attachment of this invention is particularly well adapted for use in connection with bottom dump boxes such as are supplied by various manufacturers in generally standard sizes and constructions. These boxes conventionally consist of a rectangular top body providing four vertical sidewalls and open its top and bottom, and a bottom member hinged at one end to the top body and normally closing the bottom thereof. The bottom carries feet for supporting the box from a floor and when the box is resting on its feet, the weight of the top body maintains it closed on the bottom member. A lifting lug is, however, provided on the rear wall of the top body and by pulling up on this lifting lug the rear end of the box may be raised to allow the front end of the bottom to move away from the front end of the top body and to dump the contents of the box through the space so provided.

These dump bottom boxes are conventionally designed for and intended to be handled by a fork lift truck and various auxiliary lift attachments have, in the past, been provided for use with fork lift trucks for dumping such boxes. In the use of such an auxiliary lift equipped fork lift truck, the prongs of the truck are used to pick up and transport the boxes from place to place and when it is desired to dump a box, the lifting member of the auxiliary lift attachment is raised vertically relative to the prongs to engage and raise the lifting lug on the rear wall of the box, this resulting in the rear end of the box being moved upwardly relative to the prongs to cause the desired dumping. The auxiliary lift attachments provided in the past, however, have been relatively complicated and expensive devices powered by hydraulic motors and the like and requiring separate controls. The general object of this invention is, therefore, to provide a relatively simple, easily constructed, auxiliary lift attachment the foregoing general type which attachment utilizes the normal raising movement of the lift carriage to achieve the raising movement of its lifting member, thereby eliminating the need for any additional hydraulic motors or the like.

Since the auxiliary lift attachment of this invention is particularly well adapted for use with fork lift trucks and in connection with the handling of bottom dump boxes, it has been shown and described herein in connection with such items. It should be understood, however, that the invention is not necessarily limited to such use with these particular items. More particularly, it may be used with other types of lifting devices other than fork lift trucks, such as a manually powered lift or any lift device having a generally vertical mast and a lifting carriage movable vertically relative to such mast and including a horizontally extending support means for engaging the bottom of an article to be lifted. Also, the lifting attachment is not limited to use with bottom dump boxes but may be also used with other types of dump boxes such as front dump boxes wherein the front wall of the box is swingable outwardly away from the remainder of the box to provide a dumping gate.

SUMMARY OF THE INVENTION

This invention resides in an auxiliary lift attachment for use with a lifting device, such as a fork lift truck, used to lift dump boxes and including a vertical mast and a lifting carriage movable vertically on the mast and having a generally horizontally extending support means, such as a pair of prongs, attached thereto for engagement with the bottom of a box for lifting such box as the carriage is raised. The attachment comprises a vertical track member and a lifting member movable

vertically thereof. The lifting member extends forwardly from the track member and is arranged to engage the lifting lug of a box carried by the prongs or other support means of the lifting device as the lifting member is raised. Raising movement of the lifting member is obtained by a flexible tension member having one end connected to the lifting member and passing upwardly therefrom and over a wheel rotatably supported at the upper end of the track member. The other end of the flexible member is connected to the mast of the lifting device by means which prevent it from moving upwardly beyond a given vertical limit. Therefore, as the lifting carriage and attached track member is moved upwardly beyond the point at which the other end of the flexible tension member reaches its vertical limit, the tension member is pulled over the wheel to raise the lifting member relative to the track member. Adjustment means are provided for adjusting the upper limit of movement of the other end of the flexible member so as to control the point at which the lifting member starts to move therefore and the level at which the dump box carried by the prongs or other support means is dumped.

BRIEF DESCRIPTION OF THE DRAWINGS

FIG. 1 is a perspective view of a fork lift truck equipped with an auxiliary lift attachment embodying this invention, the lifting carriage of the fork lift truck in this view being shown raised to a position at which the lifting member of the lift attachment is raised to its box dumping position.

FIG. 2 is a side view of the apparatus shown in FIG. 1, but with the lifting carriage of the fork lift truck being shown in its lowered position.

FIG. 3 is a view similar to FIG. 2 but shows the lifting carriage raised to the point at which the lifting member of the auxiliary lift attachment is raised to a box dumping position.

FIG. 4 is a vertical sectional view taken through the track member of the auxiliary lift attachment of FIG. 1, this view showing the lifting member in its lowered position.

FIG. 5 is an enlarged horizontal sectional view taken on the line 5-5 of FIG. 4.

FIG. 6 is an enlarged horizontal sectional view taken on the line 6-6 of FIG. 1.

FIG. 7 is a fragmentary rear view taken on the line 7-7 of FIG. 2 and showing the upper end of the track member and the associated crossbar.

DESCRIPTION OF THE PREFERRED EMBODIMENT

Turning to the drawings and first considering FIG. 1, this FIG. shows a lifting device in the form of a fork lift truck 10. This truck 10 is of generally conventional construction and includes a vertical mast 12 having two laterally spaced members 14, 14, these members being fixed against vertical movement relative to the remainder of the truck. A lifting carriage 16 is supported for vertical movement relative to the mast 12 and is powered by a hydraulic cylinder 18 controlled by the operator of the truck. The carriage 16 includes two horizontal plates 20 and 22, which are vertically spaced from one another, and a horizontally extending rod 24 located above the upper plate 22. The rod 24 vertically supports two forks 26, 26. Each fork 26 in turn includes a horizontally extending prong 28 and a vertically extending arm 30 with the upper end of the arm being apertured and slidably received on the rod 24 as shown. The weight of the forks, therefore, causes the arms 30, 30 to bear against the carriage plates 20 and 22 and the forks are slidable laterally along the rod 24 to vary the spacing therebetween to adjust them to the spacing required for the particular load to be picked up, the horizontal prongs 28, 28 comprising horizontally extending support means for engaging the bottom surface of an article for raising and lifting the same.

Still referring to FIG. 1, an auxiliary lift attachment embodying this invention is there indicated generally at 32. This lift attachment includes a track defining means in the form of a track member 34 attached to the carriage 16 between the

forks 26, 26 with its longitudinal axis generally vertical. Movably vertically along the track member 34 is a lifting member 36 which is engageable with the lifting lug of a dump box, not shown in FIG. 1, for raising the rear end of such box relative to the prongs 28, 28 to achieve dumping of the same. As explained hereinafter, the movement of the lifting member 36 relative to the track member 34 is coordinated with and caused by the normal raising movement of the carriage 16, and in FIG. 1 the carriage 16 is shown at a level at which the lifting member 36 is raised to its dumping position relative to the track member 34.

The construction of the auxiliary lift attachment is best shown in FIGS. 4, 5, 6 and 7 and in referring to these FIGS. it will be noted that the track member 34 is a tubular member of generally square cross section and includes a slot 38 in its front wall extending from the bottom of the member 34 for a substantial distance along the length thereof. The lifting member 36, in turn, is in the form of a trolley having a set of wheels 40, 40 located inside of the member 34 and engageable with the inside surface of said member so as to be capable of rolling in the vertical direction therealong. Preferably, these wheels are or include antifriction bearings so as to reduce the effort required to raise the lifting member 36. As shown in FIGS. 4 and 5, the lifting member projects through the slot 38 and beyond the track member 34 and has a forward portion 42 having a flat forwardly directed face 44. This face 44 is used to engage the rear wall of a dump box as the prongs 28, 28 are moved into underlying relation with the box and serves to properly position the box on the prongs so as to ensure proper engagement of the lifting member 36 with the lifting lug of the box as the lifting member 36 is raised relative to the track member 34.

The means used for attaching the track member 34 to a lifting carriage may vary widely, but where the lifting carriage is of the construction shown in FIG. 1, such means preferably comprises, as best shown in FIGS. 4 and 6, a hook 46 welded to the rear wall of the track member 34 and adapted to hook over the top edge of the top carriage plate 22, a spacer plate 48 also being welded to the rear wall of the track member 34 to space the track member a proper distance forwardly from the plate 22. Another part of the attachment means consists of a horizontal bar 50 welded to another spacer plate 52 which spacer plate 52 is in turn welded to the rear wall of the track member 34. The spacer plate 52 spaces the track member a proper distance forwardly from the bottom carriage plate 20 and the horizontal bar 50 rests on the top edge of the plate 20, it being located in the space between the two carriage plates 22 and 20.

As shown best in FIGS. 1 and 6, the bar 50 extends laterally to either side of the track member 34 and each laterally extending portion thereof extends behind the vertical arm 30 of the adjacent fork 26. The two fork arms 30, 30, therefore, prevent the bar from moving forwardly and the engagement of the spacer plate 52 with the plate 20 prevents it from moving rearwardly, the bar 50, therefore, being effectively locked in place by the plate 20 and arms 30, 30. The bar 50 is, however, of such a length that when the prongs 26, 26 are moved to their extreme outer positions, as shown by the broken lines in FIG. 6, by sliding along the rod 24, the vertical arms 30, 30 of the prongs are positioned free of bar 50 so that the bar may be removed from its place between the carriage plates 20 and 22, therefore, allowing the lifting attachment to be readily attached to or removed from the carriage simply by moving the prongs 26, 26 between the two positions illustrated in FIG. 6. Further, the bar 50 preferably includes two forwardly projecting stops 54, 54 attached respectively to the two laterally extending portions thereof with each stop being engageable with the respective one of the fork arms 30, 30 as shown. The stops 54, 54 are further so spaced from one another that when the arms 30, 30 are brought into engagement therewith the prongs 26, 26 are spaced a proper distance from one another for use in handling the dump boxes in question.

Referring to FIGS. 4 and 7, the lifting member 36 is moved relative to the track member by a flexible tension member in the form of a roller chain 56 having one end attached, as at 58, to the upper end of the lifting member 36. From the attachment point 58, the chain 56 passes upwardly through the track member 34 and passes over a toothless sprocket wheel 60 which is rotatably supported at the upper end of the track member 34 for rotation about a horizontal axis parallel to the carriage 16 by a shaft 62. Attached to the other end of the chain 56, as at 64, is a crossbar 66 which extends laterally outwardly beyond both sides of the track member 34 and is connected to the two vertical members 14, 14 of the lift truck mast 12 in such a manner that it is prevented from moving upwardly beyond a given vertical limit relative to the mast.

The means for so connecting the crossbar to the vertical mast member 14, 14 may vary but in the present instance is shown to consist of two additional flexible tension members in the form of chains 68, 68 each having one end attached to a respective end of the crossbar and having its other end connected to a hook 70 welded to the upper end of the associated mast member 14, as shown in FIG. 1. In FIG. 1, only the hook 70 attached to the left-hand vertical member 14 is shown, but it should be understood that a similar hook is also provided on the right-hand vertical member 14 at a corresponding height. Each vertical mast member 14 also has fixed thereto by welding or the like a number of vertically spaced laterally outwardly extending headed adjustment posts 72, 72, as shown on the left-hand vertical member 14 of FIG. 1, it being understood that the left-hand vertical member 14 includes a similar set of such posts 72, 72 at corresponding levels. Each chain 68 is of such a length that it extends downwardly from the crossbar 66, around one of the associated set of adjustment posts 72, 72 and upwardly to its associated hook 70. The particular adjustment post about which each chain passes is selected by the operator to control the height at which the box carried by the prongs 28, 28 is dumped, as hereinafter explained.

Having now explained the construction of the auxiliary lift attachment of this invention, its operation may be more fully appreciated by considering FIGS. 2 and 3. Referring to these figures, a bottom dump box of the type with which the lift attachment may be used is shown in broken lines at 74 and includes a lug body member 76 having an open top and an open body, and a bottom member 78 which normally closes the bottom of the top member 76 and which includes legs 80, 80 for normally supporting the box a small distance above the floor on which it rests. The bottom member 78 is connected to the top member 76 for swinging movement about a hinge axis indicated at 82 located near and extending along the bottom rear edge of the top member 76. A rearwardly extending lifting lug 84 is attached to the rear wall 85 of the top member 76.

In FIG. 2, the carriage 16 of the fork lift truck 10 is shown lowered to the position at which the prongs 28, 28 may be moved horizontally underneath the box 74 to bring them into proper position beneath the box to thereafter raise the same. In moving the prongs to this position, the fork lift truck is moved forwardly toward the rear wall 85 of the box until the forward face 44 of the lifting member engages such wall. Thereafter, the carriage 16 is raised to raise the prongs 28, 28 thereby bringing the prongs into engagement with the bottom of the dump box and lifting it off the floor. With the box so lifted the truck 20 may be driven to any location to transport the box from one place to another. Generally for such transport from place to place, the carriage 16 is raised only a small amount which is not sufficient to cause any raising movement of the lifting member 36. When, however, it is desired to dump the box 74, the carriage 16 is raised to a still higher elevation and during such raising movement it eventually comes to a point at which all of the slack is taken up in the chains 68, 68 so that further upward movement of the crossbar 66 is prevented. Therefore, as the carriage is raised still further above this limit, such raising movement will thereafter cause the chain 56 within the track member 34 to move over the

wheel 60 and thereby raise the lifting member 36 relative to the track member 34. As the lifting member 36 so moves along the track 34, it eventually engages the lifting lug 84 of the box 74 and as a result of such engagement and further upward movement raises the rear end of the box 74 and the attached rear end of the bottom member 78. Since the front end of the bottom member 78 is unattached to the body 76, this front end will not move upwardly with the body 76 with the result that the front end of the bottom 78 moves away from the body 76 to the position shown in FIG. 3 at which the contents of the box are dumped by sliding along the bottom member 78 and off the front edge thereof. Of course, at the time this dumping occurs, the fork truck will have been moved to position the box 74 above a bin, truck body, or other receptacle into which it is desired to dump the box contents. After the contents of the box are dumped, the carriage 16 is lowered, this lowering movement of the carriage lowering the lifting member 36 and returning the box to its closed position.

I claim:

1. An auxiliary lift attachment for a lifting device used to lift a dump box of the type having a lifting lug extending rearwardly from its rear wall and, which lifting device includes a generally vertical mast, a carriage movable vertically relative to said mast, and a generally horizontally extending support means on said carriage engageable with the bottom of such a box to lift it as said carriage is raised, said auxiliary lift attachment comprising means defining an elongated track, means for attaching said track defining means to a carriage such as aforesaid with its longitudinal axis extending generally vertically, a lifting member supported by said track defining means for vertical movement relative thereto, a wheel at the upper end of said track defining means and supported for movement relative thereto about a horizontal axis, a main flexible tension member having one end attached to said lifting member and extending upwardly therefrom and trained over said wheel, and means for connecting the other end of said flexible tension member to said mast to prevent it from moving upwardly beyond a given vertical limit as said carriage is raised so that as said carriage is raised beyond the point at which such other end of said flexible tension member reaches said vertical limit said flexible tension member is pulled over said wheel to raise said lifting member relative to said track defining means, said lifting member having a forward portion which is engageable with the lifting lug of a dump box such as aforesaid positioned in a normal manner on said support means so as to lift said lug and said box relative to said support means as a result of said raising movement of said lifting member.

2. An auxiliary lift attachment as defined in claim 1 further characterized by means for adjusting said vertical limit beyond which said other end of said flexible tension member is prevented from moving upwardly so as to thereby adjust the level of said carriage at which said lifting member engages and start to rise the lifting lug of a box carried by said support means.

3. An auxiliary lift attachment as defined in claim 1 particularly adapted for use with a lifting device in the nature of a fork lift truck wherein said carriage includes two horizontally extending vertically spaced plates and said generally horizontally extending support means comprises two fork members each having a horizontally forwardly extending prong and a vertically extending arm which arm bears against the forward faces of said two carriage plates and is slidably laterally relative thereto to vary the spacing between said prongs, said lifting device being further characterized by said attachment means for attaching said track defining means to said carriage comprising a hook fixed to said track defining means and adapted to hook over the top edge of the upper one of said two carriage plates, and a horizontal bar fixed to said track defining means and extending laterally from either side thereof which bar is adapted to reside in the space between said two carriage plates and to rest on the top edge of the lower one of said two carriage plates with each laterally extending portion

of said bar having a part thereof positioned behind an associated one of said vertical fork arms.

4. An auxiliary lift attachment as defined in claim 3 further characterized by each of said laterally extending portions of said bar including a forwardly extending stop for engaging the associated one of said vertical fork arms to limit the movement of said arm toward the other one of said arms, the two of said stops therefor establishing a minimum spacing for said fork arms and their associated prongs.
5. An auxiliary lift attachment as defined in claim 1 further characterized by said track defining means comprising an elongated tubular member having a slot in its forward wall extending along a portion of the length thereof, and said lifting member comprising a trolley having a set of wheels located within said tubular member and engageable with the inside surface thereof for vertical rolling movement therealong, said trolley also including a portion projecting forwardly through said slot and beyond said tubular member for engagement with the lifting lug of a dump box positioned on said associated support means.
6. A lifting attachment as defined in claim 5 further characterized by said portion of said trolley which extends forwardly beyond said tubular member including a forwardly facing face for engagement with the rear wall of a dump box such as aforesaid to limit the rearward movement of said box relative to said support means as said support means is moved forwardly into underlying relation with the bottom of such box.
7. A lifting device as defined in claim 1 for use with a lifting device wherein said mast includes two laterally spaced vertical members fixed against vertical movement, and wherein said lifting attachment is adapted to be attached to said carriage with said track defining means being located between said two mast members, said lifting attachment being further characterized by said means for connecting said other end of said main flexible tension member to said mast to prevent it from moving upwardly beyond a given vertical limit comprising a crossbar fixed to said other end of said flexible tension member and extending laterally in both directions from said track defining means, and two additional flexible tension members each connected between a respective one of the ends of said crossbar and an associated one of said two vertical mast members.
8. A lifting attachment as defined in claim 7 further characterized by a plurality of laterally outwardly extending adjustment posts fixed to each of said two vertical mast members over which posts said two additional flexible tension members may be selectively looped to adjustably vary said vertical limit beyond which said other end of said main flexible tension member is prevented from moving upwardly, each of said two additional flexible tension members having its mast connected end connected to its associated vertical mast member at a level above said laterally extending adjustment posts so as to normally extend downwardly from such attachment point, around one of said adjustment posts and upwardly to said crossbar.
9. An auxiliary lift attachment as defined in claim 1 particularly adapted for use with a lifting device wherein said generally vertical mast includes two laterally spaced vertical members fixed against vertical movement, and wherein said track defining means is adapted to be attached to said carriage between said two vertical mast members, said lift attachment being further characterized by said track defining means comprising an elongated tubular member having a slot in its forward wall extending along a portion of the length thereof, said lifting member comprising a trolley including a set of wheels located within said tubular member and engageable with the inside surface thereof for rolling movement vertically thereof, said trolley also including a portion extending forwardly through said slot and beyond said tubular member for lifting engagement with the lug of a dump box positioned on said support means, and said means for connecting the other end of said flexible tension member to said mast to prevent it from moving upwardly beyond a given vertical limit comprising a

crossbar fixed to said other end of said flexible tension member and extending laterally outwardly from beyond sides of said tubular member, and two additional flexible members each connected between a respective one of the ends of said

crossbar and an associated one of said mast members.

10. A lifting device as defined in claim 9 further characterized by said tubular member being of a generally square cross section.
